UNITED STATES PATENT OFFICE

EDWARD C. STEARNS, OF SYRACUSE, NEW YORK

SAW-SETTING DEVICE

Application filed November 17, 1925. Serial No. 69,595.

This invention relates to a saw-setting device of the lever-operated slide and rotary anvil type in which the barrel carrying the slide and anvil is provided with a depending integral handle in opposed relation to a depending lever whereby the lever and handle may be gripped by one and the same hand for forcing the slide to its setting position against the action of a suitable retracting spring.

The main object is to extend the integral handle and its cooperative lever from the barrel across the produced axis of the rotary adjustable anvil so as to bring the adjusting means for the anvil in more convenient position for adjustment by one hand while the device is held by the handle and lever in the other hand and also to enable the user to visually determine the position of different portions of the face of the rotary anvil relatively to the hammer slide than would be possible if the handle and lever extended in the same direction as the axis of the rotary anvil.

Other objects and uses relating to specific parts of the device will be brought out in the following description.

In the drawings:

Figure 1 is an end view of a saw-setting device embodying the various features of my invention.

Figure 2 is a longitudinal sectional view of the same, taken on line 2—2, Figure 1.

Figure 3 is a transverse sectional view taken on line 3—3, Figure 1.

Figure 4 is an end face view of the anvil supporting head.

Figure 5 is an inner face view of the anvil.

As illustrated, this device comprises a barrel —1— having one end provided with an integral handle —2— and its other end formed with an integral extension or head —3—, the end of the barrel —1— adjacent the head —3— being provided with a lug —4— which together with the head —3— extend in the same direction as the handle —2— but in spaced relation to each other and some distance from the handle, said barrel being provided with an intermediate

lug —4'— in spaced relation to the handle —2— and front lug —4—, Figure 2. The barrel —1— is provided with lengthwise guides or bearings —5— and —5'— for receiving and guiding a longitudinally movable hammer slide or plunger —6— the inner end of which is normal to its axis as shown in Figure 2, the bearings —5— being arranged in spaced relation for receiving a spring —7— which is coiled around the intermediate portion of the slide —6— and has one end engaged with the inner face of the lug —4— in which the bearing —5— is formed and its other end engaged with a hand pin —8—, the latter being secured in a diametrical opening in the slide —6— to project outwardly or upwardly beyond the upper face of the barrel —1— as shown in Figures 2 and 3, the lower side of the barrel between the lugs being opened to permit the removal and replacement of the spring —7—.

The bearing —5'— is also spaced longitudinally from the handle —2— for the reception of one end of a hand lever —9— which is pivoted at —10— to and between opposite or laterally spaced walls of the barrel —1— and has one end extended from the pivot —10— in the same general direction as the handle —2—.

The other or upper end of the hand lever —9— is provided with an abutment —11— engaging the inner end of the slide or plunger —6— for forcing the plunger endwise against the action of the spring —7— when the handle end of the hand lever —9— is drawn or pressed toward the handle —2—.

The outer end of the slide or plunger —6— extends through and beyond the front face of the lug —4— and bearing —5— and is provided with beveled sides —12— forming a hammer tooth for engaging and setting the teeth of the saw, the handle —2— being provided with an opening —2'— in alignment with the bearings —5— and —5'— to permit the removal and replacement of the plunger —12— therethrough.

The head —3— is integrally united to the front end of the handle by an upwardly arched yoke portion —13— and is preferably disposed in a downwardly and forwardly

inclined plane in spaced relation to the lug —4— to form an intervening saw-receiving space —14—.

This head —3— is also provided with a journal bearing —15— for the intermediate portion of a rotary spindle —16— which extends through and beyond opposite faces of the head at right angles to the plane thereof and, therefore, at an angle to and slightly below the produced axis of the slide or plunger —6—.

A circular disk or anvil —17— is eccentrically secured to the inner end of the spindle —16— to rotate therewith and is provided with an annular conical or beveled inner face —18— eccentric to its axis of rotation, all portions of which are adapted to be presented in opposed relation to the outer end or hammer face of the plunger —6— as the shaft or spindle —16— is adjusted rotarily for varying the amount of set of the saw teeth when the tooth of the plunger —6— and registering portion of the beveled face —18— of the anvil are brought into pressing co-action upon any individual tooth of the saw the portion of the beveled anvil face opposed to the plunger being also normal to the axis of the plunger as shown in Figure 2.

The outer end of the spindle —16— is provided with a knob or handle —19— by which the spindle and anvil may be turned and is also provided with a pointer —20— movable around a suitable dial —21— on the adjacent end face of the lug —3— for indicating the amount of set which may be necessary to impart to the saw teeth.

An adjusting screw —22— is mounted in a threaded aperture in the lug —4— directly below the axes of the plunger —6— and spindle —16— and has its inner end provided with a knob or handle —23— by which it may be turned.

A lock nut —24— is engaged with the screw —22— at the outer face of the lug —4— for holding the screw in its adjusted position. The outer end —25— of the adjusting screw is rounding or spherical to form a bearing for one side of the saw blade while the other side is adapted to rest against the inner flat face as —26— of the anvil —17—.

The adjustment of the screw —22— is made to compensate for varying thicknesses of saws which may be interposed between the inner flat face of the anvil —17— and bearing face —25— of the screw to serve as guides for the saw blade in shifting the same to register different teeth with the hammer end of the plunger —6—.

The barrel —1—, handle —2— and lugs —3—, and —4—, together with the yoke —13— and hand lever —9— are preferably made of cast iron while the remaining parts are made of suitable metal such as steel hard-

ened at the ends where they contact with the saw blade or teeth of the saw for strength and durability.

The yoke —13— is provided with a vertical sight opening —13'— therethrough registering with the anvil —17— and adjacent end of the slide —6— to enable the operator to properly register the independent teeth of the saw with the adjacent faces of the slide —6— and anvil —17—, the lower edges of the yoke being disposed in a transverse plane slightly above the upper face of the hammer end of the slide —6— to form a limiting stop for the saw blade when the latter is pressed in operative position for setting the teeth thereof and thereby assuring a uniform depth of set of said teeth.

A sheet metal plate —27— is slidable endwise of and upon the upper face of the barrel —1— and has its forward end offset downwardly at —28— and provided with an aperture for receiving the adjacent end of the slide —6— which serves to hold the front end of the plate against upward displacement while permitting its longitudinal movement.

The rear end of the plate —27— is provided with an upwardly extending handle portion —28'— by which the plate may be moved longitudinally.

The intermediate portion of the plate is provided with a series of in this instance three lengthwise parallel slots —29—, —30— and —30'— which are connected at their rear ends by a transverse slot —31—, the slot —29— being arranged along the longitudinal center of the plate while the slots —30— and —30'— are arranged equal distances from and at opposite sides of the central slot.

These slots —29—, —30— and —30'— and also the transverse slot —31— are adapted to receive the upwardly projecting end of the hand pin —8— on the slide —6— while the walls of each slot serve to hold the pin and slide in any of its angularly adjusted positions.

That is, the central slot —29— serves to hold the slide —6— in position for setting what may be termed straight teeth while the slots —30— and —30'— serve to hold the slide at different angles for setting reversely inclined teeth.

The plate —27— is preferably made of spring metal and is provided with a lock pin —32— adapted to engage in an aperture —33— in the upper side of the barrel for holding the plate in its locking position against endwise movement and thereby holding the slide —6— in any position of adjustment with the pin in its corresponding slot in the plate.

Operation

The eccentric anvil —17— is first adjusted

5 rotarily according to the amount of set which it may be desired to impart to the teeth of the saw after or before which the slide —6— may be adjusted rotarily to bring its hammer end into proper position for setting straight or

reversely inclined teeth.

10 The blade of the saw is then placed in operative position between the adjacent faces of the anvil —17— and screw —22— with the teeth of the saw between the hammer end of the slide —6— and registering portion of the anvil —17—, it being understood that the screw —22— has been previously adjusted to assist in properly guiding the saw when

15 shifting it for registering the teeth to be set with the slide and anvil.

20 While the saw is being placed in operative position for setting the teeth thereof the handle —2— is placed in the palm of the hand while the trigger or lever —9— is gripped by the fingers of the same hand and drawn toward the handle —2— thereby forcing the slide —6— forwardly against the action of the retracting spring —7— for setting the 25 registering tooth of the saw against the registering portion of the anvil —17—, the slide —6— and its operating lever —9— being retracted to their normal positions immediately upon the release of the pressure upon the 30 hand lever. The handle —2— and hand lever —9— extend substantially the same distance from the pivot —10— and in the same direction and enables the user to firmly hold the device with one hand while the other hand 35 is free to shift the saw endwise as may be desired for setting the teeth thereof.

What I claim is:

40 A saw-setting device comprising a barrel having a top wall, a handle secured to and extending downwardly from the rear end of the top wall at approximately right angles thereto, a lug secured to and extending downwardly from the front end of the top wall of the barrel, an intermediate lug secured to and 45 extending downwardly from the top wall of the barrel in spaced relation to the handle and front lug, said lugs having aligned guide openings, a saw-setting plunger slidable in said guide openings, a hand lever pivoted to the barrel between the handle and intermediate lug for operating the plunger to its saw-setting position, a spring in the space between the lugs for retracting the plunger, and an 50 annular supporting head integral with the front end of the barrel positioned in front of and in spaced relation to the front lug in combination with an anvil eccentrically journaled in said head to rotate about an axis inclined to the path of movement of the 55 plunger.

56 In witness whereof I have hereunto set my hand this 6th day of November, 1925.

EDWARD C. STEARNS.
